DESIGN FOR A COMBINED SOAP CAKES AND DISPLAY PACKAGE UNIT

Daisy Baker Hay, Anniston, Ala.

Application December 21, 1945, Serial No. 124,920

Term of patent 3½ years

(Cl. D58—2)

To all whom it may concern:

Be it known that I, Daisy Baker Hay, a citizen of the United States of America and a resident of the city of Anniston, in the State of Alabama, have invented a new, original, and ornamental Design for Combined Soap Cakes and Display Package Unit, of which the following is a specification, reference being had to the accompanying drawings, forming part thereof, wherein

Figure 1 is a top plan view of the combined soap cakes and display package unit showing my new design;

Figure 2 is an end elevational view thereof; and
Figure 3 is a side elevational view.

I claim:

The ornamental design for a combined soap

cakes and display package unit, substantially as shown.

DAISY BAKER HAY.
